Inventor:
Dall Worthington,

Joseph W. Hazell
Atty.

UNITED STATES PATENT OFFICE.

DALL WORTHINGTON, OF BALTIMORE, MARYLAND.

PIPE.

Application filed January 24, 1925. Serial No. 4,431.

To all whom it may concern:

I, DALL WORTHINGTON, a citizen of the United States, residing at Baltimore, in the county of Baltimore and State of Maryland, have invented certain new and useful improvements in Pipes, of which the following is a specification.

The present invention relates to tobacco pipes, and has for one of its objects to provide a smoking pipe with means for absorbing moisture and saliva and preventing the same from flowing back through the smoke passage to the mouth.

Another object of the invention is to provide a smoking pipe with an absorbent device which may be conveniently inserted and which is easily grasped for removal.

Still another object of the invention is to provide such a pipe with absorbent means in the interior thereof without any unusual or objectionable conformation of the pipe.

A further object of the invention is to provide a pipe with moisture-absorbing means which is adapted to be of a definite formation and which lies partly within the stem of the bowl portion and partly within the mouthpiece.

Still another object of the invention is to provide a pipe consisting of a bowl and stem member and a mouthpiece member, one of said members having a portion adapted to enter the other, preferably in the form of a cylindrical reduced portion with a passage through the center thereof adapted to contain a formed absorbent member, whereby in assembling the bowl and stem member and mouthpiece member one may be rocked or rotated with respect to the other until they are in an assembled position without deforming or otherwise affecting the formed absorbent member which lies within both sections of the pipe.

Other objects and advantages of the invention will in part be apparent and in part appear from the following detailed description taken in connection with the accompanying drawings, which illustrate by way of example a preferred embodiment of the invention and in which:

Fig. 1 is a vertical longitudinal section taken through one form of pipe embodying the present invention;

Fig. 2 is a sectional view taken on the line 2-2 of Fig. 1;

Fig. 3 is a perspective view of the mouthpiece or bit member showing the smoke

passage therein and showing a preferred form of absorbent member associated therewith.

Referring in detail to the drawings, in the form of the invention herein illustrated, the tobacco pipe comprises the usual bowl member 11, the interior 12 of which is adapted to receive a supply of smoking tobacco and having associated therewith and preferably integral with said bowl portion a stem 13.

The pipe is preferably formed in two sections, one being the bowl section above described and the other being the mouthpiece 14.

One of these members or sections is adapted to enter the other when the pipe is assembled and is therefore provided with a reduced portion 15, herein shown as being provided on the mouthpiece and being cylindrical in shape and adapted to be received within a cylindrical opening 16 provided for that purpose in the stem member. The bowl and stem may be formed of any suitable material, preferably wood, and the mouthpiece is preferably formed of hard rubber, though it will be understood that the specific material of which the pipe is made may be varied in practice as may be desired.

The cylindrical connecting portion 15 preferably fits tightly but removably in the opening 16 and in practice when the pipe is assembled, its assembly is usually facilitated by rocking or rotating one section of the pipe with respect to the other, and at the same time urging the connecting portion 15 into position.

The bowl and stem section is provided with a longitudinal smoke passage 17, and the mouthpiece 14 is provided with a longitudinal smoke passage 18, said smoke passages being adapted to register with each other when the pipe is assembled for the purpose of providing a clear and unobstructive passage for the smoke from the bowl of the pipe through the end of the mouthpiece.

In accordance with the present invention, a second compartment or passage is provided for the reception of an absorbent member 19. In the preferred form of the invention herein shown, the bowl and stem section is provided with a passage 20 adapted to receive an absorbent member, said passage being hereinafter referred to as the stem ab-

sorbent passage for purposes of convenient identification, and this passage is preferably arranged to hold within it and retain therein a formed absorbent member, such as that shown at 19, and which may conveniently consist of wire wound with absorbent material. In addition to being formed to retain therewithin the absorbent member, the stem absorbent passage is preferably arranged below and in open communication with the stem smoke passage 17.

The mouthpiece 14 is similarly provided with a mouthpiece absorbent passage 21, which is also preferably formed not only to receive but to retain the other end of the absorbent member and is also in open communication with the mouthpiece smoke passage 18. The mouthpiece absorbent passage is shown as extending nearly to the end of the mouthpiece, but ending short thereof in order to leave a substantially thick portion for wear that may be caused by the teeth of the smoker clamping on the end of the mouthpiece.

In separating and assembling the sections of the pipe for purposes of cleaning and inserting a fresh absorbent member, the processes of separating and assembling the sections is often facilitated by rocking or rotating one section with respect to the other and at the same time urging the sections longitudinally. An important object of the present invention is to provide an absorbent in the form of a pipe cleaner such as is now in common use in order to eliminate a collection of saliva and sediment in a well in the pipe, which is most objectionable to clean, to eliminate soft or what may be termed unformed absorbent members, which must be picked out of the pipe by an implement or otherwise removed with difficulty and in a soggy and dirty condition; and to provide, first, an absorbent member having some definite shape in order that it may be easily handled for insertion or removal, second, an absorbent member which will protrude beyond the end of one section or the other when the sections are separated in order to facilitate grasping it for removal.

It will therefore be seen that when the absorbent passage in both sections is so located that it passes through the center of the reduced connecting portion as shown in the drawings, the pipe sections may be rocked or rotated when they are assembled or separated without jamming, distorting, or otherwise disturbing the absorbent member. The smoke passages in each section are arranged above the absorbent passages and are so located that they will register with each other to form a single uninterrupted passage from the bowl to the mouthpiece when the sections are in an assembled position.

The particular type of absorbent member preferably used is of the ordinary pipe

cleaner type and consists of spirally wound wire and absorbent material with space between the spirals to receive saliva in order that the sides and bottom of the absorbent member as well as the top, as it lies in the absorbent passage, will function as an absorber.

In the preferred embodiment of the invention herein described, it will be noted that the absorbent member does not interfere in any way with the cleaning of the smoke passage by the usual method, namely, by the insertion and withdrawal of the usual straight pipe cleaner.

It will be seen that the present invention provides a pipe in separable sections, one of which is adapted to hold part of an absorbent member and the other of which is adapted to hold the other part, so that when the sections are separated, the absorbent member will protrude rigidly or substantially rigidly from one of the sections, being thus in a position where it can be readily grasped and thrown away and a new absorbent member inserted; and it will also be seen that the absorbent-containing passages are so arranged that the absorbent member lies in the center of the reduced connecting portion by which the sections are secured together so that it will be unaffected by any rocking or rotating movement that may be employed to facilitate the assembly of the sections; that the smoke passage is in communication with the absorbent passage substantially throughout its length, but that at the same time the absorbent passage is so shaped that it will retain therein the absorbent member and prevent it from becoming displaced into the smoke passage, thereby leaving the smoke passage free and unobstructed at all times so that it may be cleaned with a pipe cleaner in the usual way; and, finally, that these results are achieved wholly within the pipe itself without the employment of any unusual exterior formation.

What is claimed is:

1. A pipe including a mouthpiece portion and a bowl member having a stem portion, each of said portions having a smoke passage and an absorbent passage communicating therewith, each of said absorbent passages being adapted to receive a portion of an absorbent member, means for connecting said portions, said absorbent passages being located centrally of said connecting means.

2. A pipe including a mouthpiece portion and a bowl member having a stem portion, each of said portions having a smoke passage and an absorbent passage communicating therewith, each of said absorbent passages being adapted to receive a portion of an absorbent member, means for connecting said portions, said absorbent passages being located centrally of said connecting means whereby said portions when connected may

be rotated relative to each other without disturbing an absorbent member located in said absorbent passages; and said smoke passages being adapted to register when said sections are assembled.

3. A pipe including a mouthpiece portion and a bowl member having a stem portion, each of said portions being formed with a smoke passage and an absorbent passage communicating therewith throughout its

length, means for connecting said mouthpiece portion and stem portion, said portions being relatively rotatable, said absorbent passages being always in registration when said portions are connected, and said smoke passages registering with each other only when said portions occupy predetermined relative positions.

In testimony whereof I affix my signature.

DALL WORTHINGTON.
